C. A. RIGGS.
RAILWAY TIE AND FASTENER.
APPLICATION FILED AUG. 30, 1915.

1,171,653.

Patented Feb. 15, 1916.

UNITED STATES PATENT OFFICE.

CHESTER A. RIGGS, OF BANNER, KANSAS, ASSIGNOR OF ONE-HALF TO WILLIAM A. RIGGS, OF BANNER, KANSAS.

RAILWAY-TIE AND FASTENER.

1,171,653.

Specification of Letters Patent. Patented Feb. 15, 1916.

Application filed August 30, 1915. Serial No. 48,029.

To all whom it may concern:

Be it known that I, CHESTER A. RIGGS, a citizen of the United States, residing at Banner, in the county of Trego and State of Kansas, have invented certain new and useful Improvements in Railway-Ties and Fasteners, of which the following is a specification, reference being had to the accompanying drawings.

10 This invention comprehends certain new and useful improvements in metallic railway ties and fasteners and it has for its primary object a durable and efficient construction of device of this kind wherein the parts 15 are so arranged that they may be very easily manufactured and readily assembled to fasten the rails in place, as well as easily removed, when desired.

20 A further object of the invention is an improved rail fastener which may be easily inserted in place and which will automatically lock itself in position after being inserted in the opening formed for it in the tie and the invention also aims to generally 25 improve devices of this class so as to render them more useful and commercially desirable.

With these and other objects in view, as will be more fully understood as the description proceeds, the invention consists in 30 certain constructions, arrangements and combinations of the parts that I shall hereinafter fully describe and claim.

For a full understanding of the invention, 35 reference is to be had to the following description and accompanying drawings, in which,

Figure 1 is a longitudinal sectional view of a railway tie and rail fastener embodying 40 the improvements of my invention; Fig. 2 is a bottom plan view of the tie; Fig. 3 is an end view of the tie; Fig. 4 is a detail view of one of the rail locking devices; and Fig. 5 is a fragmentary longitudinal section of the 45 tie, showing how a wrench is applied in the operation of removing the rail fastening devices.

Corresponding and like parts are referred to in the following description and designated in all of the views of the accompanying drawing, by like reference characters.

Referring to the drawing, the numeral 1 50 designates my improved tie which is preferably hollow, as shown and constructed of

steel, whereby it will combine strength with 55 lightness to a marked degree, said tie being formed with a plurality of openings 2 extending therethrough and arranged in two pairs, one pair near each end of the tie in the required position, whereby the openings 60 will lie on opposite sides of the track rails in a convenient manner. The openings 2 may be of any desired size and shape and are preferably rectangular and they open at their lower ends in enlarged counter-sinks 3, 65 as best illustrated in Fig. 2.

4 designates the rail locking or fastening devices. Each of these comprises a shank 5 which is preferably rectangular and of a size to snugly fit in one of the openings 2, 70 and a head 6 which is flat or rounded at the top, whereby it may be easily driven into place and which is formed with the usual lug to engage the base flange of the rail. The shank 5 is formed near its lower end 75 with an opening 7 extending therethrough from back to front and above each end of this opening and registering therewith, a recess 8 is formed. Each fastening device is provided with a locking spring 9. These 80 springs are received and held in the openings 7, being first inserted therethrough in a flat or straight condition and the ends being subsequently turned up while hot, whereby said ends will tend to spring out and project 85 from the front and rear faces of the shank 5, as clearly illustrated in the drawings. As is obvious, when the shanks 4 are inserted into the openings 2, the locking ends 10 of the springs 9 will be accommodated in the recesses 8 hereinbefore referred to, and when the fastening devices are driven down to a certain point, it is manifest that the ends 10 will spring out into the counter-sinks 3 and thus lock the fastening devices in place, 90 whereby the rails will be very securely and rigidly held in position. By providing the counter-sinks 3, the locking ends 10 of the springs are prevented from spreading out 95 too far which, of course, would defeat the 100 purpose for which they are designed.

From the foregoing description, in connection with the correlated views of the accompanying drawing, the operation of applying my improved fastening devices to 105 the tie to hold the rails in position, will be apparent. To remove the fastening devices, I preferably employ a wrench desig-

nated 11, as a whole. This wrench is in the form of a bar, which is preferably of somewhat angular formation, as shown, having a handle portion 12 at one end and at its other extremity being provided with a cup 13 which is designed to be pressed upwardly upon the shanks and against the springs 9 so as to compress their protruding ends 10, whereupon as is obvious, the 10 fastening devices may be withdrawn and the ties released. Co-acting with the bar of the wrench 11 and forming part of the wrench, is a hook 14, said hook being formed with an opening 15 extending therethrough and with a nib or lug 16 formed in the bottom wall of the opening and designed for engagement with either one of a pair of notches 17 formed in the lower edge of the bar whereby the hook may be adjusted 15 lengthwise of the bar, according to whether the wrench be used for withdrawing the inner fastening device or an outer one. In using this wrench, the bar is disposed underneath the end of the tie and the hook 14 engaged with the edge thereof at the top, whereupon by pressing down upon the handle 12, it is evident that the cup 13 may be made to engage the projecting ends 10 of the adjoining spring 9 and said ends 20 retracted so that the fastening devices may be easily taken out.

While the accompanying drawing illustrates what I believe to be the preferred embodiment of my invention, it is to be understood that the invention is not limited thereto, but that various changes may be made in the details of construction, arrangements and proportions of the parts, without departing from the spirit of my invention, as defined in the appended claims.

Copies of this patent may be obtained for five cents each, by addressing the "Commissioner of Patents, Washington, D. C."

Having thus described my invention, what I claim is:—

1. The combination with a railway tie having an opening formed therein, of a rail fastening device insertible in said opening, and a spring carried by said fastening device and adapted to automatically spring out into engagement with the tie below the opening upon the insertion of the fastening device into the opening. 45

2. The combination with a railway tie of a rail fastener therefor, the tie being formed with openings extending therethrough and with counter-sinks at the lower ends of the openings, and fastening devices being insertible in said openings and provided with springs having upwardly and outwardly movable ends adapted to spring out into the counter-sinks upon the insertion of the fastening devices into said opening. 55

3. The combination with a railway tie having openings extending therethrough and terminating at their lower ends in counter-sinks, of rail fastening devices, said fastening devices including shanks insertible in said openings and having openings passing therethrough, and recesses above and communicating with the ends of said openings, and springs extending through said openings and having upwardly projecting ends adapted to be accommodated in said recesses, and to spring out into the countersinks upon the insertion of the fastening devices into the opening. 60

In testimony whereof I hereunto affix my 75 signature in the presence of two witnesses.

CHESTER A. RIGGS.

Witnesses:

JAMES W. HAWKES,
R. J. TAGUE.
